UNITED STATES PATENT OFFICE.

WILLIAM R. SMITH, OF BUFFALO, NEW YORK.

BREECH-LOADING ORDNANCE.

No. 797,237.

Specification of Letters Patent.

Patented Aug. 15, 1905.

Application filed May 12, 1905. Serial No. 260,127.

To all whom it may concern:

Be it known that I, WILLIAM R. SMITH, of Buffalo, in the county of Erie and State of New York, have invented certain new and useful Improvements in Breech-Loading Ordnance, of which the following is a specification.

This invention relates to improvements in ordnance, and particularly to guns of the breech-loading type, and to means for cleaning out the bore of such guns automatically, with a view also to preventing the "flare-back" from the breech of the gun of any gaseous or other material remaining in the gun after the discharge.

The object of this invention is to provide a gun or other piece of ordnance with means for admitting fluid under pressure, such admission being effected by the initial pressure of the explosion in the firing-chamber through either the recoil of the gun or the direct pressure of the explosion. In attaining this object of the invention I preferably employ electrical connections for the direct operation of the fluid-pressure-controlling valve, the electric circuit being established upon such explosion in the firing-chamber.

Another object of this invention is to provide means for automatically forcing a charge of lubricant into the firing-chamber along with the compressed air.

Another object is to provide means for automatically increasing the pressure in the compressed-air reservoir by the explosion effected by the discharge in the firing-chamber, the expansive effect of said explosion acting upon the charge of compressed air in the reservoir to increase its density.

To these ends my invention consists in the construction and combination of parts substantially as hereinafter described and claimed.

Of the accompanying drawings, Figure 1 represents a longitudinal section of a portion of a well-known type of eight-inch breech-loading rifle having my improvements applied thereto, said figure representing also a longitudinal section of a reservoir for compressed air or other fluid, said figure representing also the connections hereinafter described, and illustrating one embodiment of my invention for attaining the objects above mentioned. Fig. 2 represents a detail elevation of a portion of a Hotchkiss recoil-gun,

said figure representing modifications hereinafter described.

Similar reference characters indicate the same or similar parts in both figures.

The body of the gun, which may be of any type, is represented at 10. In Fig. 1 the breech-plate 11, breech-plug 12, mushroom-head 13, and its stem 14 are illustrated as of a common type. The bore of the gun is represented at 15 and the firing-chamber at 16.

Through the walls of the body of the gun are formed openings 17, preferably inclined, as shown, for the same purpose as in my application filed February 20, 1904, Serial No. 194,510, said openings being provided with suitable check-valves 18 and connected at their outer ends to pipes 19, as also shown in my said application. Connections, preferably flexible, are represented at 20, said connections leading to the pipes 19 from a pipe 21, having a balance valve or cock 22, said pipe 21 leading from a reservoir 23 for compressed air or other suitable fluid under pressure. Hereinafter I shall refer to the reservoir 23 as a "compressed-air reservoir;" but it is to be understood that, if desirable, some other fluid than air may be employed.

The arm 24 of the valve 22 may be actuated by hand, so as to admit air from the reservoir to the pipes 19 and through the openings 17 into the bore of the gun, said arm being, however, connected by means of a link 29 with the lever 27, pivoted at 28 to a suitable support, said lever having at its other end an armature 26 of an electromagnet 25. The arm 24 may be actuated by hand to open the valve, either by grasping said arm and swinging it or by operating the lever 27 in a direction that would move the armature 26 toward the magnet. Usually, however, the valve 22 is to be automatically opened by mechanism actuated by the initial pressure of the explosion in the firing-chamber of the gun. The means which I have shown in Fig. 1 for performing this function comprises a plug 32, mounted to reciprocate slightly in a suitable opening leading through the wall of the gun from the firing-chamber, said plug having a head 33 snugly fitting in a slight recess in the wall of the firing-chamber 16. The plug 32 is shown as provided with a stop nut or shoulder 34 in its outer end to limit the inward movement of the plug 32 to a point where the inner face of the head 33 will not

project beyond the wall of the firing-chamber. A spring 35, suitably secured to the gun and bearing at its outer end upon the outer end of the plug 32, normally holds the plug in the position shown in Fig. 1. A contact-strip 36 overlaps the end of the spring 35 and is also mounted upon the gun, being supported thereon by an insulating-block 37.

The spring 35 and contact 36 are connected with the magnet 25 by suitable wiring. As shown in Fig. 1, the wire *x* connects one pole of the magnet with the contact 36, and the wire *y* connects the other pole of the magnet with the spring 35, a battery or other source of electricity being shown at 30, located in the connection *y*. The connections *y'*, hereinafter described more fully in detail, lead from the connection *y*, a switch 31 being employed, so as to cut out the connections *y'* when desired. When the connections *y'* are cut out, the switch 31 will be in the position indicated by full lines; but when the circuit is to include the connections *y'* the switch 31 will be moved to the position indicated by dotted lines.

Assuming that the switch is in the position indicated by full lines, the operation will be as follows: The air-reservoir 23 having been charged through a suitable connection 42 by means of any air-compressor (not shown) and the gun being loaded and fired, the initial pressure in the firing-chamber acting on the head 33 of the plug 32 forces the spring 35 outward, so as to contact with the terminal 36, and thus establish a circuit through the battery 30 and the magnet 25, immediately attracting the armature 26 and opening the valve 22 and admitting compressed air to the pipes 19, from which the air will flow through the openings 17 past the check-valves, thereby preventing any flare-back, cleaning out the bore of the gun and cooling it. When the supply of air has been continued long enough, the valve 22 may be closed by hand, because immediately after the pressure is relieved in the firing-chamber the spring 35 separates from the contact 36 and breaks the circuit, thereby releasing the armature, so as to permit the closing of the valve.

As hereinbefore stated, one of the objects of this invention is to provide means for increasing the pressure in the air-reservoir at the instant of the discharge in the gun. One embodiment of this feature of my invention comprises a movable partition 38, similar to a piston, located in the air-reservoir 23, said partition having a guide-stem 39 leading through the stuffing-box 40. To limit the movement of the partition or abutment 38 toward the left when the air is being compressed into the air-reservoir through the connection 42, the said reservoir may be provided or formed with an annular shoulder 41. The particular object of limiting the movement of the partition or abutment 38 is to provide a space

for a suitable explosive cartridge 45, so that said cartridge will not be injured by pressure against it of the partition 38. To introduce this cartridge 45 into the chamber or space provided for it, I have illustrated a holder 44 externally screw-threaded and fitting a threaded opening in the end of the reservoir, said holder 44 having a shallow recess in its inner end, which may be threaded, so that the cartridge 45 can be screwed into said recess. Said cartridge may be of any type which will be exploded by an electric current, and for this purpose the holder is shown as provided with insulated wires 46, one of which will contact with the center of the cartridge and the other with the rim thereof, the cartridge being suitably constructed so that when a circuit is established through the cartridge and the wires 46 the cartridge will be exploded, the force of the explosion acting upon the partition or abutment 38 and forcibly and suddenly increasing the pressure of the air in the other portion of the reservoir. In order that the products of combustion due to the explosion of the cartridge 45 may be allowed to escape after the gun has been fired and when the air is being compressed into the reservoir 23, I may provide a suitable cock, as indicated at 43, which cock can be opened by hand and then closed after the partition 38 has been forced to the shoulder 41 by the operation of the air-compressor (not shown) forcing air into the reservoir through the connection 42.

In order that the electric connections with the wire 46 may be readily separated to permit of the unscrewing and return of the cartridge-holder 44, the connections *y'* are shown as having terminal plugs 47, removably fitting suitable sockets in the holder 44, which sockets connect with the wires 46.

It will now be understood that if the switch 31 is in the position indicated by dotted lines when the electric circuit is completed at 35 36, as hereinbefore described, not only will the magnet 25 be caused to open the air-valve 22 to admit air to the gun, but at the same time the cartridge 45 will be exploded, so as to suddenly increase the pressure of the air in the reservoir and in the connections to the bore of the gun, thereby rendering it unnecessary to preserve the high pressure of air in the reservoir 23 prior to the firing of the gun.

One or more lubricant-chambers may be connected with the air-conduits in order to introduce suitable material into the gun with the air to prevent corrosion of the bore of the gun after the air has passed through. In Fig. 1 I have represented two lubricant-chambers 48, connected with one of the pipes 19, the connection of each chamber with said pipe being controlled by a hand-operated valve 49. Said chambers may be located at any suitable point in connection with the air-conduits. A lubricant, such as glycerin, is placed in the

chamber 48, and just prior to each discharge of the gun the valve 49 will be opened to permit some of the lubricant to flow into pipe 19 or other conduit, after which the valve 49 will be closed. Upon the discharge of the gun and the passage of air through the pipes or conduits, as hereinbefore described, the air will take up the said lubricant and spatter it along through the bore of the gun. This lubricant may be of any composition which will form a film or coating to prevent oxidation. It is to be understood, however, that the lubricant may be introduced at any time after the discharge of the gun. For instance, the valve 49 need not be opened until after the gun has been fired and after the valve 22 has been closed. Then the valve 49 may be opened to admit some of the lubricant to the air-conduit, after which the valve 22 may be opened slightly by hand to admit a small quantity of compressed air to the conduits, just enough to coat the bore of the gun with lubricant.

Referring to Fig. 2, 50 represents the mount of a well-known type of Hotchkiss gun which I have selected for illustrating the feature of my invention which I shall now describe. The ways on which the gun recoils are indicated at 51. The contact 52 is carried by a suitable portion of the gun which travels along the ways 51 when the gun recoils, said contact 52 being connected with a wire *y* of an electric circuit. A spring-contact 53, secured at one end upon an insulating-block 54, secured to the gun-mount, is connected with the wire *x* of the electric circuit. In this embodiment of my invention when the gun recoils upon the initial pressure of the explosion in the firing-chamber the sliding contact 52 meets the spring-contact 53 and slides along it, thereby completing the circuit and energizing the magnet 25, so as to open the air-valve 22 in the same manner as has been described above in connection with Fig. 1.

It is to be understood that in the accompanying drawings I have not attempted to show some of the parts or connections other than conventionally. The number and location and amount of inclination of the openings 17 may be varied to suit the requirements of the particular gun to which the invention is applied or to meet the views of the constructor.

Therefore I do not limit myself to the details of construction illustrated and above described.

I claim as my invention—

1. A gun having a firing-chamber and bore, a fluid-pressure reservoir and means operated by the initial pressure of an explosion in the firing-chamber for admitting fluid under pressure from the reservoir to the firing-chamber.

2. A gun having a firing-chamber and bore, a fluid-pressure reservoir, connections between the reservoir and the firing-chamber, a valve controlling said connections and means operated by the initial pressure of an explosion for opening said valve.

3. A gun having a firing-chamber and bore, a fluid-pressure reservoir, a conduit connecting the reservoir with the firing-chamber and means for introducing a lubricant into said conduit.

4. A gun having a firing-chamber and a bore, a reservoir for fluid under pressure connected with the firing-chamber and means operated by an explosion in the firing-chamber for increasing the pressure in said reservoir.

5. A breech-loading gun having an opening through its body into the bore independent of the breech-block, a source of compressed air connected with said opening, and means operated by the initial pressure of the firing charge in the gun for admitting air to the gun through said opening, a manually-operable valve being employed whereby air may also be admitted before or after the explosion.

6. A breech-loading gun having an opening through its body into the bore independent of the breech-block, a compressed-air reservoir connected with said opening, a valve for controlling the passage of air from said reservoir to the opening of the gun, and electrical connections adapted to be actuated by the initial pressure of an explosion of the firing charge in the gun to open said valve.

In testimony whereof I have affixed my signature in presence of two witnesses.

WILLIAM R. SMITH.
